Attest.

United States Patent Office.

MARTIN LANDENBERGER, OF PHILADELPHIA, PENNSYLVANIA.

Design No. 4,443, dated October 25, 1870.

DESIGN FOR A DRESS-TRIMMING.

The Schedule referred to in these Letters Patent and making part of the same.

To all whom it may concern:

Be it known that I, MARTIN LANDENBERGER, of Philadelphia, in the county of Philadelphia and in the State of Pennsylvania, have invented certain new and useful Improvements in Design for Dress-Trimmings; and do hereby declare that the following is a full, clear, and exact description thereof, reference being had to the accompanying drawing, and to the letters of reference marked thereon making a part of this specification.

The nature of my design is fully illustrated by the accompanying drawing; and

It consists in the application of a knotted fringe to both sides of so-called "piece-goods" or "dress-goods," sold by the yard.

A represents a piece of dress-goods, cloth, or piece of goods whatsoever, on both sides of which woven with the goods, is a knotted fringe, B.

What I claim as new, is—

The design for dress-goods, as shown and described, that is, with a knotted fringe woven with the goods on both edges thereof, as set forth.

In testimony that I claim the foregoing, I have hereunto set my hand, this 12th day of September 1870.

MARTIN LANDENBERGER
